UNITED STATES PATENT OFFICE.

KIRK D. BISHOP AND ALBERT G. CLASS, OF CLEVELAND, OHIO, ASSIGNEES
TO SAID BISHOP.

PRESSURE-REGULATOR FOR AIR-COMPRESSORS.

SPECIFICATION forming part of Letters Patent No. 229,083, dated June 22, 1880.

Application filed December 13, 1879.

To all whom it may concern:

Be it known that we, KIRK D. BISHOP and ALBERT G. CLASS, of Cleveland, in the county of Cuyahoga and State of Ohio, have invented 5 certain Improvements in Pressure-Regulators for Air-Compressors, of which the following is a specification.

The first part of our invention relates to a device for regulating or maintaining a uniform 10 pressure in an air-receiver when the compression of the air therein is effected by the admission of water or other inelastic fluid under pressure.

The second part of our invention relates to 15 a device to be used in connection with the aforesaid pressure-regulator and a reciprocating, oscillating, or vibrating compressor, and to be operated thereby, for directing the flow of the compressing-fluid into that chamber or 20 part in which the air-pressure has been reduced by drawing off; and our invention therein consists in the peculiar construction, arrangement, and combination of the various operative parts of our device, as more fully herein- 25 after described and shown.

In order that persons skilled in the art may know how to make and use our device, we will now proceed to fully describe the same, reference being had to the accompanying drawings.

30 Figure 1, Sheet 1, is a perspective view, showing our devices as arranged for use in connection with an oscillating double compressor, such as is employed for compressing air into beer-barrels by admitting water under pressure into the chambers alternately. Fig. 35 Fig. 2, Sheet 2, is a vertical section through the valve which directs the flow of the compression-water into either of the oscillating chambers shown in elevation behind it. Fig. 3 is 40 a longitudinal vertical section of the pressure-regulator. Fig. 4 is a transverse vertical section of the same and of the delivery-valve. Fig. 5 is a vertical section of the regulator piston and its stem removed from the cylinders. Fig. 6 is a detached sectional elevation 45 of the delivery-valve.

In the drawings, A and A' represent two cylindrical chambers or receivers, in which the air may be compressed by the admission of 50 water under pressure through the flexible

tubes B B'. These compressing-chambers are mounted at either end of an oscillating beam, A², having trunnions journaled in the top of a forked standard, A³.

A delivery-pipe, A⁴, connected with the upper 55 part of each compressor, with an outwardly-opening check-valve for each, conducts the compressed air from one at a time to the beer-cask in which it is desired to maintain a constant and unvarying air-pressure until its 60 contents have been entirely drawn off.

The compression of the air in the receivers A A' is effected through the alternative admission of water under pressure into their lower parts from the pipes of the ordinary or 65 municipal supply.

The air-compressors shown form no part of 70 the present invention, but are introduced to show the applicability of our newly-invented regulating devices, the first of which, the pressure-regulator, we will now proceed to describe.

The regulator consists of three superposed cylinders, C C' C², the lower one, C, being considerably greater in bore than the others, and separated from them by spacer-posts. 75

A cup-leather, a, forms a packing for each joint, as well as for the cup-piston D and its hollow stem or piston-rod D'. At b, in the middle cylinder, C', there is an inlet for water under continuous pressure, which may be 80 taken from the municipal service-pipes. In the larger or lower cylinder there is an outlet through the delivery-pipe c.

At d ports are drilled in the stem D', which is 85 pressed downward by a weighted lever, E, acting on its upper end; or an adjustable spring may be used for that purpose.

When the hollow stem and piston are moved down so that the ports d are below the packing a at the top of the middle cylinder, water 90 will flow through them down into the cylinder C, whence it is conducted by the pipe c toward the compressors, following the course of the arrows shown in Fig. 4.

It will be evident that so long as the pressure in the air-compressors is below the limit to which the piston is loaded the water will 95 continue to flow to the compressors until that limit is reached, when the back-pressure will raise the piston to the position seen in Fig. 3, 100

and cut off the further admission of water. This regulator will therefore maintain a uniform pressure in the air-compressor with which it may be connected at any desired point less than the pressure due to the head of the compressing-fluid passing through. Acting as it does by or through the back-pressure, compression will be uniform, although the head of the compressing-fluid may fluctuate.

10 The enlarged or cup-shaped piston D renders the valve much more sensitive to changes in the back-pressure than if the stem D were carried down into the lower cylinder. When used in connection with the class of compressors shown it becomes necessary to provide a means for automatically directing and changing the flow of the compressing-fluid as may be required. To this end we take three superposed cylinders, F F' F², and secure them together by outside bolts passing through both heads, which, as well as the two intermediate joints, are packed with cup-leathers e, as seen in Figs. 2 and 4. A plunger, G, plays through both heads, motion being given it by a lever, H, at its upper end, engaging with two studs, g, on one of the compressing-chambers; or any equivalent means may be used to give the plunger the required movement at the proper times. The central portion of the plunger is 25 hollow, and into it two series of ports, f f', are drilled, as seen in Figs. 2, 4, and 6. The delivery-pipe c from the regulator enters the middle chamber, F'. An outlet, h, connects the upper chamber, F², with the compressing-chamber A, through the flexible tube B, and a similar outlet, h', connects the lower chamber,

F, with the compressor A', through the flexible tube B'.

The cup-leathers e prevent the water from passing directly from the middle chamber, F', into the others; but it is conveyed into one or the other through the two sets of ports f f' as the plunger is moved up or down, thence to either compressor.

The entire apparatus is mounted in a shallow tray, I, provided with a waste, i, so that the water discharged from the compressors and all waste and leakage may be carried off.

What we claim as our invention is—

1. An air-compressor regulator consisting of 50 cylinders C C' C², having openings b c, hollow piston-rod D', with its ports d and cup-piston D, and weighted lever E, constructed, arranged, and operating substantially as and for the purpose set forth.

2. In combination with an oscillating air-compressor, the regulator constructed as described, and the cylinders F F' F², openings e h h', hollow plunger G, and ports f f', substantially as described and shown.

3. The cylinder F F' F², with its openings e h h', and the hollow plunger G, with its ports f f', in combination with a regulating-valve for admitting water under pressure therein, and an oscillating air-compressor, and a means 65 for operating said plunger, substantially as set forth.

KIRK D. BISHOP.
